MACHINE FOR STRIPING ELECTRIC CONDUCTORS

Robert A. Donnan, Worcester, Mass., assignor to Surprenant Mfg. Co., Boston, Mass.

Application April 29, 1949, Serial No. 90,392

16 Claims. (Cl. 118—221)

1

This invention relates to machines for producing distinctive markings, such as variously colored helical stripes, on electric conductors and the like, and it is the general object of the invention to provide a machine of this type which will operate with stationary sources or supplies of ink or other striping fluid.

In a striping machine which has already been proposed, striping disks engage and are rotated by the wire or conductor to be striped as it moves along the axis of the machine. The disks are mounted on a rotating unit containing an ink well and an inking pocket for each disk. As the unit turns the ink rises from the wells by centrifugal force into the pockets to ink the disks as the latter revolve around the wire. The striping capacity of that machine is limited by the amount of ink the wells can hold, and when long wires are being striped it is necessary to stop and open the machine from time to time to replenish the ink supply. Furthermore, it is found that the pigments used in certain inks tend to separate by centrifuging and cling to the sides of the wells and the inking pockets or chambers in which the disks rotate. Such a striping machine is shown in Patent No. 2,537,884 issued January 9, 1951, and copending application Serial No. 82,732, filed March 22, 1949.

It is an important object of the present invention to construct the striping unit of such a machine so that the pockets can be supplied with ink from stationary ink reservoirs exterior to the unit while the latter is in operation. The ink in the pockets is thus replenished and the machine is able to run continuously to stripe wires of any desired length.

It is a further object of the invention to cause ink to flow through the rotating unit to reduce or prevent centrifuging of the pigment of the ink. When this feature of the invention is used discharge outlets are provided to enable the ink to flow out of the rotating unit in such manner as to avoid flooding of the ink pockets.

It is a still further object of the invention to locate the outlet from each pocket in such position as to maintain the desired depth of ink in the pocket and thereby insure proper inking of the periphery of the striping disk.

It is another object of the invention to provide the striping unit with a plurality of ink receiver compartments into which ink flows from corresponding reservoirs and connect each compartment to an ink pocket, each pocket thereby receiving ink from its reservoir through its compartment. A stationary delivery tube for each

2

reservoir extends into the associated compartment to deposit ink in the latter as the receiver rotates with the striping unit.

It is still another object of the invention to collect the ink discharged from the striping unit and return it to the source, thereby keeping the ink in continual motion to prevent settling or objectionable centrifuging of the pigment.

When the ink is to be changed in any of the pockets a cleaning fluid or ink solvent can be run through the corresponding receiver, pocket and passages and discharged from the machine into the associated collector. The cleaning fluid enters the pocket in a direction generally tangential to the disk and turns the latter to expose all of its periphery to cleaning action. At such times there will ordinarily be no wire in the machine and the disk will be free to turn.

It is another object of the invention to provide each reservoir with a control valve to regulate the amount of ink flowing to the corresponding pocket, therefore wide and narrow disks using different amounts of ink can be employed in different pockets and an amount of ink correct for each disk can be supplied to its pocket.

It is a further object of the invention to provide a striping machine wherein several striping patterns can be produced on successive sections of a single wire without stopping the machine.

The wire being striped may be of large or small diameter, and the lay of the spiral stripes may be long or short. These varying conditions require corresponding changes in the angle of the disks relative to the wire.

It is a further object of the invention to provide for changing the angle of the disks by a ring gear rotatable on the unit and meshing with pinions connected to carriers on which the disks rotate. By rotating the gear on the unit the carriers and therefore the axes of the disks can be turned to change the angle of the planes of the disks to suit various conditions of wire size and lay of the stripe.

Wires of different sizes require that the disks be at different distances from the axis of the machine, and it is a still further object of the invention to provide a second ring gear and pinions therefor to move the carriers and disks in a radial direction to adapt the disks to wires of different sizes. Suitable clamping means are provided to keep each of the ring gears in their adjusted positions.

More specific objects of the invention are to provide an improved striping unit comprising similar ink pocket forming blocks, and an ink

receiver means built up of a plurality of similar members forming the aforesaid compartments.

In order that the invention may be clearly understood reference is made to the accompanying drawings which illustrate by way of example the embodiments of the invention and in which:

Fig. 1 is a front elevation of a striping machine made according to the present invention,

Fig. 2 is a plan view looking in the direction of arrow 2, Fig. 1,

Fig. 3 is an enlarged horizontal section on line 3-3, Fig. 1,

Fig. 4 is an enlarged vertical section on line 4-4, Fig. 3,

Fig. 5 is a horizontal section on line 5-5, Fig. 4, omitting certain of the structure,

Figs. 6 and 7 are enlarged horizontal sections on lines 6-6 and 7-7, respectively, of Fig. 4, parts being broken away in each figure,

Figs. 8 and 9 are detail vertical sections on lines 8-8 and 9-9, respectively, Fig. 6,

Fig. 10 is a vertical section on line 10-10, Fig. 9,

Fig. 11 is a detail vertical section on line 11-11, Fig. 6,

Fig. 12 shows an electric conductor of a type which can be striped on the machine,

Fig. 13 is an enlarged detail vertical section on line 13-13, Fig. 2,

Fig. 14 is an enlarged fragmentary section similar to part of Fig. 4,

Fig. 15 is a diagram showing the relation of the ink in one of the pockets and the associated compartment when the machine is in operation, and

Fig. 16 shows a wire diagrammatically with four different striping patterns such as can be produced while the machine is in continuous operation.

The machine to be described hereinafter has for its general purpose the striping of electric conductors or wires an example of which is shown in Fig. 12. In order that the wire W may be readily identified it is provided with helical marking stripes which may be either of the same or diverse colors. In Fig. 12 three stripes S1, S2, and S3 are shown, but the machine can produce one, two, three or four stripes each of a different color, or in various combinations, and the stripes can be either wide or narrow. The various parts of the machine for striping such a wire forming the subject matter of the present invention will now be described.

Frame and driving mechanism

Referring particularly to Fig. 1, the frame of the machine includes a table 10 supported in horizontal position by legs 11 at least one of which supports a bracket 12 on which a driving motor M is mounted. By a belt 13 the motor drives a pulley 14 secured to the striping unit U to be described in detail hereinafter.

The electric conductor wire to be striped, designated at W, is wound on a reel 15 rotatable on a stand 16, and is led around a guide sheave 17 and then up along the axis of unit U. After being striped the wire continues upwardly through a drying or heating chamber H and then extends down and is guided by sheaves 18 to a wind-up mechanism T which acts as a feed means to draw the wire through the striping machine at a rate which is in timed relation with the rate of rotation of unit U, the timed relation being variable.

A platform 19 is mounted on the upper ends

of support arms 20 the lower ends of which are secured to the table 10. Braces 21 secured to arms 20 stiffen the latter and resist objectionable vibration of the platform during operation of the machine. Platform 19 is formed with a central opening 22 through which the wire passes.

Striping mechanism

The striping unit U is shown more particularly in Figs. 4 and 6-8. A hollow vertical bearing column 25 has a horizontal flange 26 at its upper end bolted as at 27 to the table 10. Within the column is a hollow shaft 28 rotatable about a vertical axis on ball bearings 29 on the column. The lower end of shaft 28 has the pulley 14 keyed thereto as at 30 and held in position by a support nut 31 threaded to the lower end of the shaft. Shaft 28 has a bore 32 through which the wire W moves upwardly and into the upper end of which is screw threaded a guide plug 33 for the wire.

Although ball bearings 29 have been shown in Fig. 4 the machine is not limited to this form of bearing, but whatever type of bearing is used it should be able to support the hollow shaft so that there will be little or no vertical play or longitudinal motion of the shaft.

The upper part of the hollow shaft is formed with an integral horizontal flange 35. Resting on the flange is a pocket forming block 36 above which is a similar block 37. These blocks are circular as shown in Figs. 6 and 7 and are formed with communicating cavities which provide inking pockets. The flange and blocks may be considered as forming a head A, see Figs. 1 and 4, for the striping unit.

Block 36 has four cavities 38, 39, 40, and 41 all connecting with a central opening 42, see Fig. 4, which extends vertically through the block. The lower surface of each of the cavities 38-41 curves downwardly and toward the machine axis as at 43, see Fig. 4, and each cavity is offset from a radius parallel to the sides 44 thereof. Thus, in Fig. 7 cavity 38 is offset to the right while cavity 40 is offset to the left, and the other two cavities are similarly offset.

The upper block 37 is formed with cavities 45, 46, 47 and 48 similar to the cavities in block 36, but offset in the opposite direction. The upper part of each cavity 45-48 is curved as at 49, see Fig. 4. Block 36 has a flat top surface 50 which fits closely against the flat bottom surface 51 of the upper block 37. Screws 52 passing down through the upper and lower blocks 37 and 36 are tapped into the flange 35 and hold the blocks fixed to the hollow shaft 28, see Fig. 11.

As indicated in Fig. 8 a lower cavity is offset from its corresponding upper cavity in such a way as to form a chamber which extends generally in a direction diagonal or oblique with respect to the machine axis. These chambers, indicated at 55, 56, 57, and 58 in Fig. 6, having their outer ends remote from the machine axis formed as inking pockets 59, 60, 61 and 62.

Each chamber has located therein a striping disk the function of which is to produce a stripe on the wire passing through the machine, or at least give it lateral support to hold the wire on the machine axis. The four disks 65, 66, 67, and 68 are arranged as shown in Fig. 6 with the inner parts of their peripheries located near the axis of the machine at an inking station S and with the outer parts of their peripheries in their respective inking pockets.

Each disk is rotatably mounted on a carrier 10 having a forked inner end supporting two ball bearings 11 and 12 through which extends a pin 13 on which the associated disk is mounted. The disks are thus rotatably mounted on their carriers so that any point on a disk periphery can turn through the inking station S and the corresponding inking pocket.

The carriers are each formed with a shank 15 which fits snugly into a bearing 16 formed partly in each of the blocks 36 and 37. Each shank is rotatable and also slidable longitudinally in its bearing and is controlled as to angular and longitudinal position by mechanism to be described.

Stationary ink supplies or reservoirs

The inking pockets are supplied with striping ink from stationary tanks or reservoirs which are mounted on the platform 19 in such manner that, if desired, they can be replaced with other tanks holding differently colored inks. In Figs. 1 and 2 ink tanks are shown at 80, 81, 82, and 83. Each tank is positioned between end bars or cleats 84 secured to the platform and is limited in outward motion from the machine axis by a stop bar 85 also secured to the platform.

A lock is provided for each ink tank or reservoir to hold it in fixed position on the platform, see Fig. 13. A small stand 86 secured at 87 to the platform has a lock 88 pivoted thereto at 89. The lock will normally be down to hold the associated tank against stop bar 85. When it is desired to remove the tank the lock will be raised and the tank slid along the platform toward hole 22 a short distance and then lifted off the platform.

Leading from the bottom of each tank is a delivery or feed tube or pipe having a control valve 90 therein by which ink flow can be varied as to rate, or stopped. The feed pipes are shown at 91, 92, 93, and 94 and extend from their respective tanks toward the axis of the striping unit and then down through hole 22.

As shown herein the ink tanks are above unit U, and ink flows toward the latter by gravity, but the invention is not limited to gravity feed of the ink, and it will be sufficient for the purposes of the invention if conditions exist wherein ink tends to flow in the feed pipes 91-94 toward the receiver mechanism now to be described when the valves 90 are open.

Ink receiver mechanism

As shown in Fig. 4 there is mounted on top of the striping unit a means for receiving ink from the tanks and conveying it into the inking pockets.

The receiver means, designated at R, is built up of several similar ring like members 95, 96, 97, 98, and 99 arranged one over the other and concentric with the axis of the striping unit. Bottom member 99 has a circular flange 100 held firmly to the top block 37 by screws 101. The previously described screws 52 also pass through flange 100.

Each receiver member has an outer vertical circular wall 105 through which extend vertically four bores 106, 107, 108, and 109. Extending inwardly and upwardly from the wall 105 is an inclined floor 110. The members are each provided with flat tops 111 and bottoms 112, respectively, which are held in close fit by bolts 113 passing through holes 114 in all the members and secured into the top block 37. The bores 106-109 are equally spaced angularly around the wall 105, and the holes 114 are likewise equally spaced but

are located midway between the bores, see Fig. 5.

The floors 110 are arranged to form four ink compartments which are shown at 115, 116, 117, and 118. Each compartment communicates by a single inlet passage 119 with but a single bore in the associated wall 105. The elements 95-99 are assembled with their inlet passage in angularly staggered relation and with the bores in walls 105 vertically aligned in groups to form four vertical ink ducts. Each of the four ducts thus formed communicates with but one compartment. Thus, in Fig. 4 compartment 117 connects with the duct 120 shown at the left, and compartment 118 connects with the duct 121 shown at the right. In Fig. 5 compartment 115 is shown as connecting with duct 122. Similarly, compartment 116 connects with a duct 123 shown at the bottom of Fig. 5. For a further understanding of the ducts, it may be stated that each duct is formed by five bores the top and bottom ones of which will be repeats of either bore 106, 107, 108, or 109, and the other three of which will be one each of the remaining bores.

The upper part of block 37 has an ink passage 124 for each duct, connecting the latter with the corresponding inking pocket, see upper part of Fig. 4. Each ink compartment is therefore connected to but one pocket. The receiver members are all tightly bolted together and there is little or no leakage between the several compartments and ducts. The top of each duct is closed by a plug 125.

The previously described feeder pipes or tubes 91-94 have their ends bent outwardly to enter one or another of the ink compartments, one tube for each compartment. The compartments open toward the machine axis, as is apparent in Fig. 4, and are of such height as to be able to receive the ends of the tubes. Each tube is bent as at 126 in a direction away from the axis and overhangs the floor 110 under it. Ink flowing or dripping from the mouth 127 of any tube will enter its compartment and pass downwardly by gravity through the associated inlet passage and duct into the corresponding inking pocket. The openings in the compartments to receive the feeder tubes are indicated at 128, see Fig. 14.

Ink discharge and collector

An important feature of the invention resides in maintaining streams of ink flowing through the striping unit, and in order to accomplish this result provision is made for the escape or discharge and collection of ink from the bottoms of the pockets, as shown in Figs. 3 and 4.

An ink collector C secured to the table 10 as at 130, is formed with upwardly opening collector troughs, four being shown herein at 131, 132, 133, and 134. These troughs are all concentric with the axis of the machine and located at different distances therefrom. There are four discharge tubes 135, 136, 137, and 138, one for each trough and the associated ink pocket, leading from the latter in a direction away from the machine axis, to the corresponding trough.

The flange 35 of the hollow shaft has a hole or discharge passage 140 therein for each discharge tube and pocket extending preferably radially outwardly from the axis of unit U. Each hole 140 is below its pocket but connects with the latter at its inner end, as at 141. Each hole 140 has tapped into its outer end a plug 142 which fits closely around its discharge tube. The outer end 143 of the plug is tapered and screw threaded to receive a clamp nut 144 which when tightened

holds the tube in adjusted position. Each discharge passage 140 and the interior of the corresponding discharge tube provides an ink outlet passage which slopes downwardly and outwardly so that it may be drained by gravity, see Fig. 4.

Each discharge tube is bent down at 145 to enter its trough. Excess ink in any pocket will be discharged through the corresponding hole 140 and discharge tube into the associated trough due to centrifugal force when unit U is rotating. The holes 140 and discharge tubes are preferably inclined downwardly and outwardly.

Return of discharged ink to reservoir

The pigments of some inks have a tendency to collect on the outer walls of the inking pockets due to centrifuging action as the striping unit rotates, and when such inks are used, it is desirable to keep them moving through the pockets to reduce to a minimum the pigment deposition by centrifuging. The discharged ink can be handled either manually or automatically, but in either method the troughs will be provided with drain pipes shown at 150—153, Figs. 1 and 4.

When the ink return is automatic the drain pipes will each lead to a pump 155 shown at the bottom of Fig. 1. From each pump a return pipe leads to the corresponding tank or reservoir. These return pipes are shown at 156—159, Figs. 1 and 2. The pumps are driven by a separate motor MP and a driving belt arrangement shown at 160. When the pigment of the inks used show little tendency to centrifuge the feed from the tanks to the pockets can be adjusted to compensate for the rate at which ink is used in the striping operation, and in that event the pumps and motor MP will not be needed. If it is necessary to maintain a flow of ink through the machine but the pumps are not desired, the drain pipes can lead to catch basins or the like (not shown) from which the discharged ink can be returned manually from time to time to the appropriate tanks.

Operation

It is believed that the operation of the machine will be apparent from the foregoing description. The wire W from reel 15 will be inserted upwardly through guide 33, the inking station, and drying chamber, and then to the take-up which will draw the wire along the axis of the machine when the latter operates. The striping disks will be in peripheral driving engagement with the wire at the inking station to be rotated by the wire as it moves. The reservoirs will previously have been supplied with the correctly colored inks for the production of the desired color combination of stripes and the valves 90 will be opened, after which the machine will be started. Ink flowing into the receiver compartments will flow by gravity into the corresponding pockets and be kept in the latter spaced from the inking station by centrifugal force due to rotation of the unit U. The ink will soon accumulate in the pockets to a sufficient depth to ink the peripheries of the disks, whereupon the striping operation will begin.

The operator of the machine will be able to tell by observing the amount of ink in the collector troughs whether adjustments of the valves 90 is necessary. If an ink is being used the pigment of which shows little tendency to centrifuge the corresponding valve can be adjusted to admit just enough ink to compensate for that used by the corresponding disk. A disk having a wide periphery will use ink at a relatively fast rate, and its valve can be adjusted to admit ink to

the associated pocket at a relatively fast rate. Conversely, if a disk has a narrow rim the feed of ink to its pocket will be at a slower rate.

As the unit U rotates it revolves the disks 5 around the wire, and the latter, due to its motion along the axis of the unit and engagement with the disks, will rotate the latter with resultant production of helical stripes on the wire. If less than stripes are required, one or more of the inking 10 pockets will be empty, due either to closure of the associated valve or valves 90, or removal of the corresponding tank.

Fig. 15 shows diagrammatically the relation 15 between the level or wall of ink in a pocket and its associated ink passages and ink compartment. When the unit is rotating centrifugal force will cause the ink to move as far from the axis of rotation as it can, and the level or wall of ink which will be almost vertical, as indicated by line 20 L. The position of the lower end of line L is determined by the mouth 141 of discharge passage 140. The upper end of the line passes to the left of the feeder tube, the mouth 127 of the latter being between the axis of unit U and the 25 ink level. The ink in the compartment cannot therefore interfere with flow of the ink from the feeder tube, and ink will flow out of the discharged pipe before it can overflow the compartment.

Variation in striping pattern

The fact that the valves 90 are independently controllable makes possible the production of several striping patterns on a single piece of wire during continuous operation of the machine. 35 Thus, in Fig. 16 four sections I, II, III, and IV show different patterns. It might be desired, for instance, to produce 2000 ft. of wire having a single orange stripe SO, section I, Fig. 16; 2000 ft. with orange and red stripes SO and SR, section II; 2000 ft. with orange, red and green stripes SO, SR and SG, section III; and 2000 ft. with these three colors of stripes combined with a 40 blue stripe, as at SO, SR, SG and SB, section IV.

To produce such a pattern the tanks are provided 45 with these variously colored inks, and all the valves closed except that for the tank having the orange ink. After the first 2000 ft. had been striped with a single stripe of orange, and while the machine continues to operate, the valve 50 for the red ink tank will be opened to stripe the next 2000 ft. with both orange and red. In turn, the valves of the tanks having green and blue inks are then opened. There would thus be produced without stopping the machine a single piece 55 of wire having four different striping patterns.

Angular and radial adjustment of disks

The machine set forth herein is provided with 60 controls which adapt it for producing stripes of different lays on wires of various diameters. The lay is the length measured along the wire corresponding to a complete turn or convolution of a stripe. If the lay is long the angle which the stripe makes with the axis of the wire will be less 65 than with a shorter lay, the wire diameter remaining the same. With a given lay, on the other hand, the angle will increase with increases in the diameters of wires being striped. For any given lay and wire diameter the angle will be 70 determined, and the disks should be set to correspond at least approximately to this angle. The means for attaining this result are set forth in Figs. 4, 6, 9, 10, 11.

Each disk carrier shank 75 projects outwardly 75 from the striping unit and has a bevel pinion

165 connected thereto by a key 166 slideable in a key slot 167. An adjusting member in the form of a ring bevel gear 168 surrounds the striping unit and meshes with the pinions. Adjustable eccentric collars 169 are mounted on and held in adjusted angular position by screws 170 tapped into unit member 36. The eccentric collars enable the ring gear to be set into close mesh with the pinions. Clamps 171 engaging the ring gear are held against it by screws 172 tapped into member 36 to hold the gear in fixed angularly adjusted position on the unit. The correct angle for the planes of the peripheries of the disks will be known for any particular lay and wire diameter and ring gear 168 can be turned to set the disks at this angle, after which the clamps will be tightened to hold the angular setting of the disks.

The radial adjustment of the disks to accommodate wires of different diameters is effected by another set of pinions and another ring gear. The unit U has secured thereto a bearing 175 for each shank 75. This bearing is held to the unit by screws 176 and has an end or cross bar 177 provided with a bearing 178 for the shank. The latter is screw threaded at 179 to fit threads 180 cut internally on a pinion 181 which fits between the unit U and pinion 165. These two pinions fill the space between unit U and the cross bar 177, and the part of the shank extending beyond the cross bar is surrounded by a compression spring 182 which exerts an outward force on a nut 183 on the shank.

An adjustor formed as a second ring bevel gear 185 meshes with the pinions 181 which serve as positioning means for the carriers. Gear 185 is positioned by eccentric collars 186 similar to collars 169 and is clamped in angularly adjusted position on unit U by clamps 187 similar to clamps 171. Pinions 181 are held against motion in the direction of the length of the shank, by the cross bars 177 and pinions 165, and as ring gear 185 is turned relatively to the unit U the pinions turn and because of their screw thread relation with the shanks, cause the latter to move either inwardly or outwardly with respect to the axis of unit U, depending upon the direction of relative turning of adjustor gear 185 with respect to the unit. The disks are thus movable to different distances from the machine axis to have striping relation with wires of different diameters.

The two ring bevel gears and their pinions and associated parts are thus seen to provide simple means by which the disks can be adjusted angularly and radially for the striping of wires of various diameters with stripes of various lays. In effecting the adjustments it is desirable first to adjust the angles of the disks and clamp ring gear 168. The keys 166 will then prevent the shanks 75 from turning when the radial adjustment is made.

Summary

From the foregoing it will be seen that the invention provides means by which a rotating striping unit can be supplied with striping ink from stationary tanks, supplies or reservoirs exterior to the unit. Ink may be regulated to flow into the pockets in sufficient amount to compensate for the ink used by the disks, or the ink can be caused to flow through the unit in streams which prevents centrifuging of the pigment of the inks to any objectionable degree. The compartments, ducts, passages 124, pockets and discharge tubes constitute ink pathways through

unit U. When ink is controlled to flow through the unit the discharge keeps pace with the inflow and ink is kept at a uniform depth in the pockets to insure even inking of the peripheries of the disks. The receiver means R comprises several similar elements which are stacked one over the other to provide a cage like set of receivers having ink compartments opening preferably toward the machine axis and receiving ink from their respective tanks to be passed on to the associated pockets. The collector troughs receive the discharged ink, and where desired, pumps return the discharged ink to the tanks. The valves 90 permit independent control, enabling one pocket to be supplied with ink at a fast rate to correspond to a rapid rate of use of ink by a broad rimmed disk, while enabling another pocket with a narrow rimmed disk to receive ink at a slower rate. Also, by opening the valves progressively several striping patterns can be produced on one piece of wire during continuous operation of the machine. The ring gears and their pinions constitute positioning means which permit the disks to be adjusted angularly and radially to accommodate various conditions of lay of the stripe and wire diameter. When a differently colored ink is to be used in any pocket it can be flushed with a cleaning fluid introduced into the associated compartment. The inlet passages 124 are so disposed that the cleaner is directed tangentially against the disk which will be free to turn and be cleaned, since wire will not ordinarily be in the machine at this time.

Having described one form of the invention, it will be apparent that variations can be made in the various parts of the machine described without departing from the spirit of the invention.

What is claimed as new is:

- 40 1. In a wire striping machine provided with means for moving a wire to be striped along the axis of the machine, a striping unit mounted on the machine to rotate about said axis, driving means to rotate the unit around said axis, said unit comprising an inking pocket therein spaced from said axis, a striping disk mounted on the unit for rotation with respect thereto and revolved by the unit around said axis when the unit rotates with a part of the periphery of said disk; adjacent to said axis for engagement with the wire to be rotated by the latter as the wire moves along the axis and with another part of said disk extending into said pocket, a stationary striping ink reservoir, an ink receiver fixed to the unit 45 communicating with the pocket, and feed means to deliver ink from the reservoir to the receiver, ink in the reservoir passing through said feed means into the receiver and thence into the pocket to replenish the ink supply in the pocket, said driving means when rotating the unit causing ink to be held in the pocket spaced from said axis by centrifugal force to be taken up by the disk to produce a spiral stripe on the wire as the latter moves along said axis and the unit is rotated by said driving means.
2. In a wire striping machine operating with a stationary striping ink reservoir and provided with means for moving a wire to be striped along the axis of the machine, a striping unit rotatable 50 on the machine about said axis, driving means to rotate the unit about said axis, an ink receiver fixed to said unit and comprising an ink compartment therein, feed means to deliver ink from the reservoir into said compartment, said unit 55 comprising an inking pocket therein spaced from
- 70
- 75

11

said axis below and communicating with said compartment into which ink can flow by gravity from the receiver, and a striping disk mounted for rotation on the unit and revolution thereby around said axis with a part of the periphery thereof in rolling engagement with the wire to be rotated by the latter as the wire moves along the axis and with another part of the periphery thereof extending into said pocket to be inked, ink being held in the pocket by centrifugal force as the unit rotates to be taken up by the disk to produce a spiral stripe on the moving wire as the latter rotates the disk and the disk is revolved around the wire by said unit.

3. In a wire striping machine provided with means for moving a wire to be striped along the axis of the machine, a stationary striping ink reservoir, a stationary collector for ink, a rotatable striping unit intermediate the reservoir and collector comprising an inking pocket therein spaced from said axis, driving means to rotate the unit about said axis, a hollow ink receiver secured to and rotating with the unit with the interior thereof communicating with said inking pocket, the unit being provided with an outlet passage leading from the pocket away from said axis to the collector, and a wire striping disk mounted for rotation on the unit and revolved around said axis by the unit when the latter is rotating with a part of the periphery of said disk in rolling engagement with the wire to be rotated by the wire as the latter moves along said axis and with another part of the periphery of said disk extending into said pocket, ink in the pocket being held spaced from said axis due to centrifugal force when the driving means rotates the unit and being taken up by the disk to produce a spiral stripe on the moving wire as the latter rotates the disk and the disk is revolved around the wire by said unit.

4. A striping machine as set forth in claim 3, wherein means are provided to return ink from the collector to the reservoir, said return means including a pump, a drain pipe connecting the collector to the pump, and a return pipe to deliver ink from the pump to the reservoir.

5. In a striping machine having means to move a wire to be striped along the axis of the machine, a striping unit mounted on the machine for rotation about said axis and comprising an ink pocket therein spaced from the axis to be supplied with ink for a striping operation, striping means extending into the pocket to be inked to produce a stripe on the wire, a hollow ink receiver secured to and rotatable with the unit comprising an opening therein and communicating with the pocket so that ink in the receiver can flow into said pocket, stationary striping ink reservoir means comprising a part extending into said opening to deliver ink into said receiver, and driving means to rotate the unit about said axis, said driving means when rotating the unit causing ink in the pocket to remain spaced from the axis due to centrifugal force.

6. In a striping machine having means to move a wire to be striped along the axis of the machine, a striping unit mounted for rotation on the machine about said axis and comprising a pocket therein spaced from the axis to be supplied with ink for a striping operation, striping means extending into the pocket to be inked and effective during operation of the machine to produce a stripe on the wire, an ink receiver surrounding the axis secured to and rotatable with the unit above said pocket and comprising a continuous

12

opening therein around said axis, stationary striping ink reservoir means comprising a part extending through said opening into said receiver to deliver ink into the latter, the unit being formed with a passage therein down which ink can flow from the receiver into the pocket, and driving means to rotate the unit about said axis, said driving means when rotating the unit causing ink in the pocket to remain spaced from the axis due to centrifugal force.

7. In a striping machine provided with means to move a wire along the axis of the machine, a striping unit rotatable on the machine about said axis and comprising a pocket therein spaced from the axis to be supplied with ink for a striping operation, striping means extending into the pocket to be inked therein effective to produce a stripe on the wire during operation of the machine, an ink receiver secured to and rotating with the unit formed with a compartment communicating with said pocket so that ink in the receiver can flow into said pocket, said receiver surrounding said axis and formed with a continuous opening therein opening toward said axis, stationary striping ink reservoir means comprising a part extending through said opening to deliver ink into said compartment, the unit being formed with an outlet passage for excess ink below the pocket leading from the latter in a direction away from the axis, and driving means to rotate the unit about said axis, said driving means when rotating the unit causing ink in the pocket to remain spaced from the axis and causing excess ink to pass from the pocket through said passage due to centrifugal force.

8. In a striping machine provided with means to move a wire along the axis of the machine, a striping unit mounted for rotation therein about said axis and comprising a plurality of inking pockets therein spaced from and arranged around said axis to be supplied with ink for a striping operation, an ink receiver for each pocket secured to and rotating with the unit, the unit comprising an ink passage for each receiver through which the ink from the latter can flow to the corresponding pocket, a stationary striping ink reservoir for each receiver comprising a part to deliver ink therefrom to the associated receiver, striping means on the unit for each pocket extending into the latter to be inked effective during operation of the machine to produce a stripe on the wire, a separate control means for each reservoir to regulate the flow of ink therefrom to the corresponding receiver in accordance with the consumption of ink in the corresponding pocket by the associated striping means, and driving means to rotate the unit about said axis, said driving means when rotating the unit causing ink in the pockets to remain spaced from the axis due to centrifugal force.

9. In a striping machine having means to draw a wire along the axis thereof, a striping unit mounted on the machine to rotate about said axis and comprising a plurality of inking pockets therein arranged around said axis, a striping disk for each pocket effective during operation of the machine to produce a stripe on the wire, a carrier for each disk on which the latter is rotatably mounted holding the disk in peripheral rolling engagement with the wire, means on the unit mounting each carrier for angular movement about an axis thereof transverse of the axis of said unit to change the angle of the plane of the associated disk relative to the axis of said unit, a pinion on and turning with each carrier, and a

ring gear surrounding said unit meshing with said pinions and mounted on the unit for angular movement relative thereto around the axis thereof to rotate said pinions and carriers in unison to change the angle of the planes of all of said disks simultaneously relatively to said axis of the unit.

10. In a striping machine having means to draw a wire along the axis thereof, a striping unit mounted on the machine to rotate about said axis and comprising a plurality of inking pockets therein arranged around said axis, a striping disk for each pocket effective during operation of the machine to produce a stripe on the wire, a carrier on the unit for each disk on which the latter is mounted for rotation holding the disk in rolling peripheral engagement with the wire, means on the unit mounting each carrier for turning movement about an axis thereof transverse of the axis of the machine and passing through the point of engagement of the corresponding disk with the wire to change the angle of the plane of the disk relative to the axis of the machine, an adjusting member surrounding the unit and mounted thereon for angular movement relative to the unit around the axis of the machine, and operative connections between said adjusting member and all of said carriers causing the latter to turn in unison to effect simultaneous changes in the angle of the planes of the disks relative to the axis of the machine when the adjusting member is moved angularly relative to said unit.

11. In a machine for striping wires of various diameters any one of which can extend along the axis of the machine, means for moving a wire to be striped along the axis of the machine, a striping unit mounted on the machine to rotate about said axis and comprising a plurality of inking pockets therein arranged around said axis, a plurality of striping disks, one in each pocket, each disk effective during operation of the machine to produce a stripe on the wire moving along said axis, a carrier mounting each disk for rotation thereon, means on the unit mounting each carrier for radial movement relative to said axis to locate the corresponding disk in peripheral engagement with the wire extending along the axis, a ring gear surrounding the unit and mounted thereon for angular movement relatively thereto around said axis, and positioning means for each carrier including a pinion rotatable on the carrier and effective when rotated to cause said radial movement of the carrier, said ring gear meshing with each pinion and when turned relatively to said unit, depending upon the direction of turning thereof, moving all of said carriers toward or from said axis to locate all the disks for peripheral engagement with the particular wire extending along said axis.

12. In a machine for striping wires of various diameters any one of which can extend along the axis of the machine, means for moving a wire to be striped along the axis of the machine, a striping unit mounted on the machine to rotate about said axis and comprising a plurality of inking pockets therein arranged around said axis, a plurality of striping disks, one in each pocket, each disk effective during operation of the machine to produce a stripe on the wire moving along said axis, a carrier for each disk mounting the disk therefor for rotation thereon, means on the unit mounting each carrier for radial movement relative to said axis to locate the corresponding disk in peripheral engagement with the wire extending along the axis, an adjustor extending around

said unit mounted thereon for relative angular movement therearound, and positioning means operatively interposed between each carrier and said adjustor effective when the latter is turned relatively to said unit, depending upon the direction of turning thereof, to move said carriers toward or from said axis to place all the disks for peripheral engagement with the wire extending along said axis.

10. 13. A striping unit for a wire striping machine having bearing means to mount the unit for rotation about the axis thereof, said unit comprising a head formed with a wire receiving bore extending along the axis thereof and an inking pocket therein spaced from said axis, a striping disk rotatably mounted on the head with a part of the periphery thereof adjacent to said axis and with the opposite part of said periphery in said pocket, and an ink receiver secured to the head formed with an ink compartment provided with an opening extending continuously around said axis, said head being formed with an ink passage therein connecting said pocket and receiver.

14. In a striping machine including a rotatable striping unit comprising an inking pocket and effective when rotating and ink is in said pocket to produce a stripe on a wire moving along the axis of rotation of the unit, a stationary striping ink reservoir, a hollow ink receiver secured to and rotating with the unit comprising an opening extending continuously around said axis and communicating with said pocket to enable ink in said receiver to pass into said pocket, and feed means connected to the reservoir to feed ink from the reservoir through said opening into said receiver during rotation of said unit.

15. In a wire striping machine, a striping unit rotatable on the machine about an axis, means for moving a wire to be striped along said axis, 40 driving means to rotate the unit around said axis, the unit comprising an inking chamber radiating from said axis and an inking pocket in the end of the chamber remote from said axis, a striping disk in said chamber, mounting means on the unit supporting the disk for rotation relative to the unit and revolution around said axis by the unit and positioning the disk so that a part thereof is in peripheral engagement with the wire to be rotated by the latter due to movement of the wire along said axis and another part thereof extends into said pocket, a stationary striping ink reservoir, a circular ink receiver surrounding said axis secured to said unit above said pocket formed with an annular opening therein opening toward said axis, the unit being provided with a passage leading from said circular ink receiver to said pocket through which ink can flow from said receiver into said pocket, and a stationary ink delivery tube connected to said reservoir and having

60 an open end extending through said annular opening into said circular ink receiver, ink in the reservoir tending to flow through said tube and be delivered from the open end of the tube, ink flowing in said tube passing through said annular opening and being delivered into said circular ink receiver and flowing thence through said passage into said pocket and when in the pocket being kept spaced from said axis by centrifugal force due to rotation of the unit by said driving means 70 to be taken up by the disk to produce a spiral stripe on the moving wire as the latter rotates the disk and the disk is revolved around the wire by said unit.

16. In a wire striping machine operating with 75 a stationary striping ink reservoir, a rotatable

striping unit comprising an inking pocket therein spaced from the axis of the unit, driving means to rotate said unit about the axis thereof, means for moving a wire to be striped along said axis, a striping disk rotatably mounted on the unit and revolved about said axis by said unit when the latter is rotated by said driving means with a part of the periphery of said disk in rolling engagement with the moving wire and with the opposite part of said periphery extending into said pocket, a part of said pocket being under said disk nearer said axis than is said opposite part of the periphery of the disk, means on said unit providing an ink outlet passage communicating with said part of the pocket and extending away from said axis, feed means having an outlet end to deliver ink from said reservoir, an ink receiver secured to and rotating with said unit above said pocket comprising a compartment formed with an annular opening into which said outlet end of the feed means extends to deliver ink from the reservoir into said compartment, and said unit comprising an ink inlet passage connecting said compartment with said pocket, ink in said pocket being held
